WIRE GRIPPING MEANS FOR ELECTRIC WIRING DEVICES

Robert H. Bentley, Hartford, Conn., assignor to The Arrow-Hart & Hegeman Electric Company, Hartford, Conn., a corporation of Connecticut

Filed Apr. 15, 1957, Ser. No. 652,881

5 Claims. (Cl. 339—95)

This invention relates to wire attachment means for electric attachment plug receptacles and the like. Although the invention is shown in connection with a duplex plug receptacle, it will be understood that the invention is not limited to use with duplex receptacles, but is useful with wiring devices generally.

Due to increase in labor costs as well as the do-it-yourself vogue, the need has become intensified for easier and quicker attachment of wires to electric devices than is afforded by screw type terminals. A number of devices for such purpose have appeared on the market, but the need to reduce the costs and increase the reliability of securing of the wire or wires has persisted.

Therefore, an object of this invention is to provide an improved means for attaching wires to electric devices, and particularly electric attachment plug receptacles, which will enable a quick, firm and unyielding connection of the wire by a gripping member which may be readily stamped from sheet metal in one stamping operation.

Another object of the invention is to provide a jaw or strut for securing wires in the receptacles or other wiring devices, which may flex to permit the insertion and gripping of a wire, but is substantially rigid in its gripping action on attempt to withdraw the wire.

Another object of the invention is to provide an improved wire attaching means having the aforesaid characteristics which can also be flexed to release the wires by insertion of a releasing tool.

Other objects and advantages of the invention will appear as it is described in connection with the accompanying drawings.

In the drawings:

Fig. 1 is a plan view, partly broken away, of a device embodying the invention.

Fig. 2 is a perspective view of the wire gripping member used in Fig. 1.

Fig. 3 is a fragmentary transverse section view taken along line 3—3 of Fig. 1.

Fig. 4 is a transverse section view taken along line 4—4 of Fig. 1.

Referring to the drawings, the invention is shown as applied to an attachment plug receptacle of the duplex type. A two-part body of molded insulating material comprising cover and base portions 10 and 12 is hollowed out with symmetrical recesses on each side of a longitudinal center line to receive identical metal contact members 20, 20', one on each side of a central partition 16. Each contact member has pairs of spaced spring fingers 22 on each end positioned to lie under conventional parallel slots provided in the cover member. The slots are in pairs on each end of the cover to receive parallel prongs of a conventional attachment plug which, on insertion through the slots, engage the spring fingers in usual fashion as in other attachment plug receptacles.

The spring finger or contact portions 22 on each end of the members are joined by a bar portion 24 formed integrally therewith and running longitudinally of the

2

body 12 and lying flatwise alongside the inside surface of the outside wall of the body so as to be backed up by the wall when pressure is applied to the bar portion, as will presently appear.

5 To hold the bared end of conductor wire 50 against the bar portion 24, an E-shaped gripping member 30 stamped from sheet metal is provided and lies centrally on the floor of the body 12 midway between the contacts 22. Preferably the material of which the gripping member is made is harder than the wire it is to grip. Since identical gripping members are provided for cooperation with each contact member, description of one will suffice.

The outer parallel legs 31 of the wire gripping member constitute jaw portions extending laterally from the 15 ends of the connecting bar portion 33. The ends of the jaws 31 are tapered to a truncated end for biting into a conductor wire inserted between the said end and a channel or groove 26 formed in the connecting portion 24 running from back to front of the body 12. In order 20 to insert the wire, holes 14 are formed in the floor of the body 12 in substantial alignment with each of the channels or grooves 26.

Since the insertion of the wire tends to push up the 25 jaws, the gripping member is held down at both sides in the following ways. A pair of small spaced lugs 34 extend laterally from the edge of the connecting portion 33 opposite the jaws 31 and into pockets 12p formed in the central partition 16 of the body 12, and serve to hold on the floor the connecting portion side of the gripping member. On the other side of the gripping member the 30 free end of the central leg 35 is inserted under the lower or inner edge of the connecting bar portion 24 of the contact member and between it and the floor of the body. Preferably a finger is formed on the lower or inner edge 35 of the connecting bar 24 over the leg 35 by forming two cuts or slots in that edge so that the finger can extend into a small rectangular aperture 38 in the leg 35. The engagement of the finger in the aperture holds the gripping member 30 from sidewise movement over the floor of the body. At the same time, the engagement of the leg 35 with the bar portion 24 prevents movement of the bar portion forwardly.

The cover 10 rests upon the top edge of the connecting bar part 24 and holds the contact members 20, 20' in place in the base. The cover may be secured to the base 45 by any conventional means such as screws (not shown) entering into the underside of the cover from the bottom of the base through bores 19 in the base or body 12.

Since the material of which the wire gripping member 50 is formed is preferably relatively stiff and only slightly resilient, greater flexibility is imparted to the wire gripping arms 31 by punching openings running lengthwise of the jaws to remove sufficient metal to impart the desired flexibility of the jaws. The jaws are preferably 55 inclined slightly upward from the floor of the body so that as the pull is increased on the wire, the jaw is forced against the central partition 16 which, being rigid, will rigidly support the jaw as a substantially rigid strut. At such time the jaw does not flex to any noticeable or substantial extent since the stress imparted thereto is almost entirely along its length with no significant lateral component. Thus, the greater the pull upon the wire the more firmly will the end of the jaw bite into the wire.

In order to release the wires when desired, slots 18 65 are formed under the midportion of each jaw in the floor of the base for insertion of a screwdriver or other implement. Upward pressure is imparted to the jaw by engagement of the end of the screwdriver or implement with the central portion of the jaw while the gripping member 70 is otherwise rigidly held in place by the lugs 34 and securing leg 35.

Having described the invention with a desire to secure Letters Patent, what is claimed is:

1. In an electric wiring device, a conductive member to which a wire is to be connected, an insulating body comprising a cover and a base, said base being hollowed out for the reception of said conductive member and providing interior floor and side surfaces, said cover holding said conductive member in place in the base, a sheet metal wire gripping member having a leg portion with at least a part thereof being flat and lying on the floor of said base, said base having a portion overlying and holding said wire gripping member adjacent one end of said leg portion, the other end of said leg portion underlying and being held by said conductive member, said wire gripping member having a jaw portion alongside and laterally spaced from one edge of said leg portion and having an end adjacent said conductive member to grip a wire inserted between the two, said leg portion being joined to said jaw portion lying on the floor of said base by a connecting portion and holding said jaw portion in wire gripping position, and said jaw portion being inclined from said interior surface of said body and bendable toward said interior surface as an outward pull is exerted on the wire to more tightly grip the wire as the pull increases.
2. In an electric wiring device, a conductive member to which a wire is to be connected, an insulating body hollowed out for the reception of said conductive member, a sheet metal wire gripping member stamped into E-shape, lugs extending from the longitudinal edge of said gripping member into engagement with said body, means holding the end of the central leg of said gripping member whereby said central leg is prevented from moving at both its ends, the end legs of said gripping member comprising jaws having their ends engaging said conductive member to grip the wires inserted between either jaw and said conductive member, said jaws being inclined from an interior surface of the body and bendable toward that surface as an outward pull is exerted on the wire to more tightly grip the wire as the pull increases.
3. In an electric wiring device, a conductive member to which a wire is to be connected, an insulating body hollowed out for the reception of said conductive member, a sheet metal wire gripping member stamped into E-shape, lugs extending from the longitudinal edge of said gripping member into engagement with said body,

said conductive member overlying and holding the end of the central leg of the gripping member whereby said central leg is prevented from moving at both its ends, the end legs of said gripping members comprising jaws having their ends adjacent said conductive member to grip wires inserted between either jaw and said conductive member, said jaws being inclined from the interior surface of said body and bendable toward that surface as an outward pull is exerted on the wire to more tightly grip the wire as the pull increases.

4. In an electric wiring device, a conductive member to which a wire is to be connected, an insulating body hollowed out for the reception of said conductive member and providing interior floor and side surfaces, a sheet metal wire-gripping member having a leg portion held at both its ends against movement upwardly from the floor of said body, with at least a part thereof being flat and lying on the floor, said wire gripping member having a jaw portion alongside of said leg portion but laterally spaced from one edge of said leg portion and having an end adjacent said conductive member to grip a wire inserted between the two, a connecting portion lying on the floor of said body joining said leg portion to said jaw portion and holding said jaw portion in wire gripping position, a lug extending from said connecting portion into engagement with the body and holding one end of said leg portion, and said jaw portion against movement from the floor, and said jaw portion being inclined from the floor and bendable at its other end toward the floor as an outward pull is exerted on the wire to more tightly grip the wire as the pull increases.
  5. An electric wiring device as claimed in claim 4 wherein the holding of the other end of said leg portion is by said other end of the leg portion underlying and being held by said conductive member.

UNITED STATES PATENT OFFICE
CERTIFICATE OF CORRECTION

Patent No. 2,944,242

July 5, 1960

Robert H. Bentley

It is hereby certified that error appears in the printed specification of the above numbered patent requiring correction and that the said Letters Patent should read as corrected below.

Column 3, line 19, strike out "lying on the floor of said base" and insert the same after "portion", first occurrence, in line 20, same column 3.

Signed and sealed this 4th day of April 1961.
